Application November 30, 1940, Serial No. 368,075

5 Claims.

(CL. 209—6)

This invention relates to separators especially adapted for removing soft and fine materials from hard and coarse materials, such as found in various kinds of ores, and has for the primary object the provision of an efficient and inexpensive device of this character which is capable of rapidly and thoroughly separating materials of the kind specified by successively subjecting said materials to fluid baths under desired pressure and under constant agitation, the construction being such that the softer and finer materials are driven off of the coarse and harder materials and discharged from the device during the successive baths with the hard and coarse materials finally discharging from the device practically free of all fine and soft materials.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is a vertical sectional view illustrating a separator constructed in accordance with my invention.

Figure 2 is a fragmentary end elevation illustrating the discharge end of the device.

Figure 3 is a transverse sectional view taken on the line 3—3 of Figure 1.

Figure 4 is a fragmentary perspective view partly in section illustrating the means for the discharge of the fine and soft materials.

Figure 5 is a fragmentary transverse sectional view illustrating the means of rotatably supporting the cylindrical body of the device.

Figure 6 is a fragmentary transverse sectional view illustrating a type of fluid discharge nozzle which may be used in the present invention.

Referring in detail to the drawings, the numeral 5 indicates a cylindrical body or housing mounted by a supporting structure at a desired inclination and for rotation with a minimum amount of friction. The cylindrical body or housing 5 has a discharge end disposed lowermost and an intake end 7 disposed uppermost in which materials may be fed by gravitation from a sluice or trough 8. The cylindrical body or housing may be composed of a series of sections or may be constructed as one unit and is mounted for rotation on a series of rollers 9 carried by the supporting structure which includes substantially U-shaped cradle members 10 mounted on

10 abutments 11. Ring gears 12 are secured on the body or housing 5 and are engaged by pinions 13 secured on shafts 14 journaled in the cradle members 10 and one of the shafts 14 may be connected to a power source (not shown) in any well known manner so that the body or housing may be rotated during the period of separation of the materials from each other. Certain of the shafts 14 and the pinions 13 thereof further act as supports for the body or housing on the supporting structure.

At spaced intervals annular abutments 15 are secured in the housing or body to divide the latter into communicating multiple chambers. The abutments act to check the movement of material from the receiving end to the discharge end of the body or housing so that said material when in each chamber will receive a thorough agitation due to the body or housing being rotated, the materials tending to follow the rotation of the housing for a certain distance and then falling by gravitation to the bottom of the housing. Every multiple chamber within the body or housing has a plurality of discharge slots for the finer and soft materials. The discharge slots are formed in the wall of the housing or body, as indicated by the character 16, and supported over said slots by perforated outer plates 18 removably secured on the body or housing is foraminous material 17. The slots 16 are preferably located in close proximity to the abutments 15 so that the materials on leaving the preceding chamber will gravitate into the slots and the finer and softer materials will pass through the foraminous material as well as the perforated plates and fall into a trough 18' carried by the supporting structure and located directly under the housing or body.

40 The abutments 15 divide the body or housing 5 into a series of contiguous chambers C each of which comprise a relatively short foraminous section in the cylindrical wall which is located substantially immediately adjacent each annular abutment on the lower side thereof. Each chamber C also comprises a substantially continuous portion on the lower side of each foraminous section. Each foraminous section is made up of the slot 16, foraminous material 17 and perforated outer plates 18. The continuous portions adjacent the foraminous sections are designated by the reference character P.

45 The trough 18' has a desired slope and at its lowermost end is provided with a discharge pipe 19 for carrying off the soft and fine materials to a desired place.

Arranged at the discharge end of the body or housing is a trough 20 for carrying off to a desired place the hard and coarser materials.

Extending substantially centrally through the body or housing is a fluid pipe 21 supported by brackets 22 mounted on the troughs 18' and 20 and is equipped with spray nozzles 23 for discharging fluid under pressure in spray form into the various chambers of the body or housing.

It is to be understood that the pipe 21 is connected to a fluid pressure supply of any well known character and is provided with a control valve 24.

The discharge nozzles 23 may be of different types or of the kind shown in Figure 6 wherein an apertured plate 25 is secured on the pipe 21 by a clamp 26 so that the aperture thereof aligns with an aperture in the pipe. A suitable gasket 27 of the apertured type is interposed between the plate 25 and the pipe 21. A curved deflector 28 is integral with the plate 25 for deflecting the spray of fluid downwardly in the chamber of the body or housing.

It will be seen that the materials on entering the first chamber of the body or housing are given a thorough washing as well as a thorough agitation and as the materials accumulate sufficiently therein they pass into the next chamber by gravitation receiving a washing during their fall so that the fine and softer materials will be driven off of the hard and coarser materials and driven through the foraminous materials and perforated plates into the trough 18 for final discharge by way of the pipe 19. The coarse and harder materials during their gravitation through the latter-named chamber are checked and again subjected to a bath under fluid pressure again loosening finer and softer materials from the hard and coarser materials. The baths continue as the materials pass from one chamber to another and each time the materials pass or gravitate from one chamber to the other said materials under their gravitation are subjected to fluid under pressure and any soft and fine materials which become separated from the hard and coarser materials are immediately discharged into the trough 18' so that the hard and coarser materials when finally leaving the body or housing are practically free of the soft and finer materials.

It is important to note that during each bath of the materials the latter receive a very thorough and efficient agitation which with the force of the fluid pressure thereon thoroughly removes soft and finer materials from the coarser and hard materials.

In each chamber C prior to each abutment 15 an action on the material passed through the separator takes place which is similar to the attrition which occurs in a "ball mill." The continuous portion P in each chamber C may also be referred to as an attrition section. The action of a new fresh water supply in the attrition section or continuous portion P helps to further disintegrate the material to be separated and a repetition of this action in a successive series of similar operations occurs in the device. After the material to be separated piles over each abutment 15 it is passed onto the foraminous

section where it is directly subjected to a spraying action and the clay passed through the foraminous section onto a receiving chamber. The foraminous section may be relatively short in order that the separating action of the cylindrical separator be efficient and the area thereof ingeniously utilized in the most economical manner, for the major portion thereof is continuous and the amount of "ball mill" action or attrition is at a maximum. When those materials which are passed through the separator involve such a large quantity of clay material as to make for the formation of large balls of clay when the material is passed through ordinary separators, the action of the series of units within the separator in accordance with the instant invention is such that the formation of large balls of clay is minimized or entirely eliminated in view of the "ball mill" action or attrition sections being located on the upper side of each abutment and the location of the foraminous sections on the lower side of each abutment and the clay material is separated from the ore material or other materials in the "ball mill" or attrition section and is passed out through the separator after it spills over the abutment onto the foraminous section so that the clay material is separated from the ore material or other material without the phenomenon known as "balling up" of clay material.

While I have shown and described the preferred embodiment of my invention, it will be understood that minor changes on construction, combination and arrangement of parts may be made without departing from the spirit and scope of the invention as claimed.

Having thus described the invention, what I claim is:

1. In a separator, a cylinder mounted for rotation with its axis extending generally horizontally but with one end higher than the other, the higher end being adapted to act as the receiving end for the materials to be separated, a series of two or more annular abutments within said cylinder, extending transversely of the interior thereof, a series of two or more relatively short foraminous sections in said cylinder each located substantially immediately adjacent each annular abutment and on the lower side thereof, the cylinder having continuous portions on the lower side of each of said foraminous sections, means located below said foraminous sections for receiving separated material discharged there-through.

2. The structure recited in claim 1, the continuous sections of said cylinder being of greater dimension in axial direction than the dimension of the foraminous sections in the same direction.

3. The structure recited in claim 1, and means for discharging water on the material to be separated within said cylinder.

4. The structure recited in claim 1, and means for discharging water on the material to be separated within said cylinder and over said foraminous sections.

5. The structure recited in claim 1 and means for discharging water over said foraminous sections and over said continuous portions.

MICHAEL P. WALLÉ.
